(Granted under the provisions of sec. 14, act of
March 2, 1927; 357 O. G. 5)

1

My invention relates to electromagnetic relays, contactors, protective cut-outs, interrupters, and other switching devices in which the opening or closing of electric contacts is controlled by the translational or rotary movement of a magnet armature.

It is an object of my invention to provide electromagnetic switching devices capable of reliably operating with switching periods below 3×10^{-4} seconds, i. e., that require less than this extremely short time from the moment the operating current or voltage is applied to the electromagnet until the moment when the armature completes the switching operation of the contacts. Another object of the invention is to devise electromagnetic switching devices whose switching periods are as short as 5×10^{-5} seconds or less. Still other objects of the invention concern the provision of a switch design generally capable of faster performance than those heretofore available and will be apparent from the following description in conjunction with the drawing, in which:

Fig. 1 is a schematic showing of an electromagnetic switching device according to the invention with a lever type armature and two air gaps, while

Fig. 2 shows a view of the same armature at a right angle to the illustration in Fig. 1.

Fig. 3 is a diagrammatic illustration of the magnetic circuit.

As the following explanations will be more readily understood with reference to a concrete example, a general description of the device according to Figs. 1 and 2 will first be given before dealing with the novel features embodied in that device.

The illustrated device has an armature 1 firmly mounted on a pivot pin 2 which is torsionally elastic to permit the armature to be attracted by the poles 8 of an electromagnet when the coil 9 of the magnet is energized. Armature 1 carries two contacts 3 and is normally biased by its pivot pin to a position in which the contacts 3 engage respective stationary members 6. An air gap is then formed between the respective pole faces of magnet poles and armature. When the magnet is energized, armature 1 is attracted so that contacts 3 engage respective stationary members 7 while the air gap is substantially closed. Members 6 or members 7 or all these members consist of stationary contacts to cooperate with the movable contacts 3 in opening or closing a circuit to be controlled. Fig. 1 indicates the length *l* of the armature and the maximum length *g* of

the air gap, both measured along the magnetic flux path. As will be shown below, the invention requires these and other magnitudes to have a given relation to one another and to the magnetic induction in the air gap under energized conditions of the electromagnet.

While heretofore electromagnetic relays for special purposes have been constructed for a switching period of about 10^{-3} seconds, the constructional principles employed in these special relays cannot be generally applied and are not suitable for power current switches. The switching periods heretofore actually attained for power current control are within the range from some hundredth down to a few thousands of a second. Now it can be shown—and this is one of the recognitions that underlie the present invention—that even a switching period of one thousandth of a second would offer no definite advantage in connection with the usual switch constructions. Let, for example, an alternating current of a frequency of 50 C. P. S. be considered. The instantaneous value of this current at a moment which lies a thousandth of a second, that is, 18° electrically, before or after the current zero passage, still amounts to 44% of the effective current value or 31% of the maximum value. If the switching commences at this moment—and this would be necessary in order to complete the switching stroke by the time the current passes through zero—there is still a very marked stressing of the contacts. Furthermore, in power, rectifier and converter current installations, the velocities of current increase due to disturbances in the nature of overloads and short-circuits may have the order of 1 to $10 \cdot 10^6$ amperes per second. This means that within a thousandth of a second the current may increase up to 10,000 amperes, that is, generally speaking up to many times the rated current. This is of great importance when, for example, impedances must be so rapidly switched in by such a device that the short-circuit current assumes only a small proportion of what its value would otherwise be. Extensive tests have furthermore illustrated that in three-phase current installations during the period of a thousandth of a second immediately prior to the zero passage, double-pole arc short-circuits are converted to a large percentage into three-pole arc short circuits, whereas in a period of less than $3 \cdot 10^{-4}$ sec. a transition from two-phase to three-phase short-circuits is practically no longer expectable. This is an important recognition for the use of synchronous control or switching devices in multi-

2

phase installations. In multiple phase contact rectifiers, for instance, the commutation period, expressed in electric angular degrees, amounts to about 15°, corresponding to 0.83 mili-sec. Consequently, only switching periods considerably below a thousandth of a second, and in particular less than 3×10^{-4} sec., allow the initiation of the circuit interruption at a moment when the current has dropped to a small fraction of the rated current value. For mechanical rectifiers, in particular, the switching periods should be below 10^{-4} sec. For relays for synchronous control and devices for suppressing the short-circuit current by rapid switching-in of impedances, the switching periods should preferably be in the order of 5×10^{-5} sec. or less.

While, as mentioned, the conventional electromagnetic switching devices have switching periods considerably higher than 3×10^{-4} sec., the invention affords the just-mentioned desirable reduction to much smaller time values and thus provides the technical and economical advantages apparent from the foregoing. This is achieved by the means and in the manner explained presently.

The switching period t of devices of the kind here dealt with can be expressed with sufficient accuracy by a magnitude A hereinafter referred to as the design magnitude and a second magnitude D which is hereinafter referred to as the dimensioning magnitude: $t = A \times D$. The design magnitude A is, to a large extent, independent of the dimensioning of the switch element but is greatly dependent upon the mass distribution, the ratio of the magnetic to the electrically conductive masses, and the angle between the resulting magnetic field in the air gap and the longitudinal axis of the armature. The dimensioning magnitude D which is given by the following equation:

$$D = \frac{\sqrt{lg}}{B}$$

is of particular importance for attaining small switching periods. In this equation, l indicates the length of the armature in cm.; g the length of the air gap in cm., which in many cases is practically equal to the switching travel, and B the mean value of the magnetic induction in the air gap. It is here presumed that the cross-section and pole surface of the armature are practically of equal size, so that the magnetic induction in the armature and in the air gap are also approximately equal.

In devices according to the invention, for instance as shown in Fig. 1, the dimensioning magnitude D in order to attain switching periods of less than 3×10^{-4} sec., is smaller than 1.5×10^{-5} cm./gauss. In other words, the invention requires that the magnetic length l of the armature and the magnetic length g of the air gap be rated relative to each other and to the mean magnetic induction B so that the value

$$\frac{\sqrt{lg}}{B}$$

is below 1.5×10^{-5} cm./gauss. Since the induction B depends upon the energization or saturation conditions of the magnet as well as on the magnetizable cross-sectional area, it will be understood that the just-mentioned correlation, for any given magnetizing condition, places the magnetizable cross-sectional area of the armature in a given limit relation to the above-men-

tioned lengths. For still smaller switching periods of, for example, 10^{-4} sec. or less, the armature is preferably designed for a dimensioning magnitude D smaller than 0.5×10^{-5} cm./gauss; in many cases, it is advisable if the length l of the armature is at the most 1 cm. It is also often advisable to provide a length g of the working air gap of at most 0.01 cm. If it is desired to avoid rebound of the contacts the switching travel will preferably lie below that limiting value at which rebounding takes place at the existing inherent dampening effect of the material used. Finally, the mean induction B in the armature or working air gap is preferably given a value of at least 10,000 gauss. For example, with $l=1$ cm., $g=0.01$ cm., and $B=10,000$ gauss, a dimensioning magnitude $D=10^{-5}$ cm./gauss is obtained.

As mentioned, the design magnitude A plays also a part with respect to the switching period t . However, this magnitude cannot be varied within such wide limits as the dimensioning magnitude D . Of particular influence relative to magnitude A is the positioning or type of movement of the switch element. The movement of the switch element or armature may be either translational or rotary. Other things being equal, the design magnitude is a maximum with a purely translating movement of the armature, since then the whole mass of the armature must be accelerated. Consequently, for short switching periods a positioning of the armature is often preferable that provides for rotary movements, in particular about the centre of gravity or about a pivot axis close to the centre of gravity. In many instances, devices are particularly suitable which require the fewest possible ampere turns for actuating the armature. This is obtained with advantage by means of an armature which rotates approximately about one end (see pivot 2 in Fig. 1), the air gap at this end amounting to at most $\frac{1}{10}$ of the working air gap. If the armature serves to actuate contacts disposed at both ends of the armature, the appertaining positioning or pivoting means are preferably designed to provide two or three freedoms of movement for the armature, as will be explained below with reference to the example shown in Figs. 2 and 3. It is also preferable to keep the entire movable mass of the armature structure as small as possible. To this end, the armature may also serve as a current conductor and carry the movable switch contacts at its respective ends. This may make it necessary, for improving the electric conductivity, to provide the armature structure with good conducting masses, for example, of copper or silver. Such masses should amount at most to $\frac{1}{3}$ of the mass necessary for magnetic purposes. The contacts are preferably made so light that their mass is at most $\frac{1}{10}$ of the mass necessary for magnetic purposes. In an extreme case, practically the entire current can be conducted by the magnetizable material of the armature and only thin coatings or platings need be provided on the contact surfaces, so that the additional masses for current conduction and contact formation are practically negligible. In order to obtain the most favorable magnetic attraction, the armature structure is so arranged with respect to the poles of the magnet that the angle between the magnetic attractive force and the longitudinal axis of the armature is greater than 70°, that is, the attractive force, as far as possible, should be perpendicular to the longitudinal extension of the armature. With arma-

tures which rotate about their centre of gravity and which have only negligible mass in addition to the mass necessary for magnetic purposes, arrangement magnitudes A of 12 gauss·sec./cm. are obtained. If at the same time the dimensioning magnitude D has the value of about 0.4×10^{-5} cm./gauss, switching periods in the order of 5×10^{-5} sec. can be obtained. When applying the device for switching power current, the electric longitudinal resistance of the armature structure should at most be equal to the total contact resistance under maximum contact pressure. For a rapid resetting of the armature, the resetting or biasing force, though smaller than the magnetic driving force, should amount at least to 20% of the magnetic driving force. If the resetting force is an elastic biasing force, the switching period can be kept at a minimum by a design whose additionally movable elastic mass comes into action with at the most $\frac{1}{5}$ of the masses of the armature structure necessary for magnetic purposes.

The features mentioned in the foregoing paragraph are embodied in the illustrated device which will now be described more in detail.

As mentioned above, the armature 1 is mounted on a pivot pin 2 . This pin consists of a thin torsion spring of such a slight bending strength that the armature cannot only rotate, but can also deflect at least in one, but generally in two directions. That is, the armature has at least two freedoms of movement. The two contact pieces 3 of the armature are connected together by a strip or plate 4 of good conducting material. The laminations 5 of the armature consist of iron or other good magnetizable material, and are called upon to assist as current conductors. The stationary members or contacts 6 limit the movement of the armature and this determines the length g of the air gap. As mentioned, in order to ensure the smallest possible switching periods, the entire armature structure is rigid and the additional mass of the movable contacts 3 and of the good conducting plate 4 should amount to only a small proportion of the mass of the laminations 5 . Furthermore, the angle between the magnetic axis of the armature and the direction of the magnetic field in the working air gap is greater than 70° . The design magnitude A of this embodiment independent of the dimensions, amounts to about 10 gauss·sec./cm. It follows from the equation of the dimensioning magnitude D , that the product of the length l of the armature 1 and the length g of the air gap must be as small as possible. These requirements are readily satisfied with the illustrated design. With a length l of 1 cm., an air gap length g of 0.01 cm. and a mean induction B of 10,000 gauss, a device according to the drawing has a switching period of about 10^{-4} sec. When the coils of the electromagnet are excited, assuming that the time constant of the control circuit is less than the desired switching period, the armature commences to rotate counterclockwise. One of the two movable contacts 3 will first come into contact with the corresponding stationary contact 7 . Due to the low bending stiffness of the torsion spring 2 , or more generally expressed, since the movable system has at least two freedoms of movement, the second contact 3 comes immediately thereafter in touch with the pertaining stationary contact. The working air gap is then fully closed on both sides and the circuit is closed. If, on the contrary, an interruption of the circuit is desired, the abutments 8 form

stationary contacts. As soon as the magnetic field is excited, the interruption process commences. An interruption, however, can also be effected by the spring force if the contacts 7 are supplied with current; the interruption then takes place when the magnetic field disappears. If the conditions are suitable for an arc-free interruption, the interruption can be terminated appreciably before the armature reaches the end of its travel. The attainable interruption periods may lie even below 10^{-5} sec.

While in the illustrated example, I have shown elastic biasing means for the armature, other resetting forces, such as a magnetic bias, gravity, or centrifugal force may be used for this purpose.

Devices according to the present invention can be employed in multiple arrangements, for instance, with relays of all kinds, protecting cutouts, regulators, switches for low and high voltage, rectifiers, converters, choppers and the like devices in multi-phase circuits.

As an explanatory addendum to the foregoing description of the invention, the following elucidations of the above-given formulae may be of interest to those desiring a further study.

As mentioned, the switching period t can be expressed with sufficient accuracy as a function of a design magnitude A and a dimensioning magnitude D : $t = A \cdot D$. It will now be shown how this equation can be developed. To this end, see Fig. 3, the following values will be used:

l =length of armature

g =length of air gap (switching travel)

A_0 =area of pole face

A_s =cross sectional area of armature

B =magnetic induction in the gap

m =mass of armature related to the center of the air gap

F_m =magnetic pull

F_f =total spring bias force related to the center of the air gap

ρ =density (specific weight)

μ =permeability

With an armature pivoted about its gravity axis and spring biased to open position, it may first be assumed, in approximation, that the magnetic induction drops instantaneously to zero at the moment when the spring force F_f overcomes the magnetic pull F_m and the armature starts turning away from the magnet poles to the illustrated position. Then the armature movement is controlled only by the spring force F_f which can be expressed as:

$$F_f = 2 \cdot A_0 \cdot \frac{B^2}{2\mu} = mg; m = \frac{1}{3} A_s \cdot \rho \cdot l$$

By integrating twice and applying the limit condition: $g=0$ for $t=0$, the gap distance or switching travel g can be expressed as a function of time:

$$g = \frac{F_f \cdot t^2}{m \cdot 2}$$

from which the switching period t results as:

$$t = \sqrt{\frac{2mg}{F_f}}$$

By substitution, this equation can be expressed thus:

$$t = \sqrt{2 \cdot \frac{1}{3} \cdot \frac{A_s \cdot \rho \cdot g}{B^2} \cdot \frac{2 \cdot A_0 \cdot \mu_0}{A_s} \cdot \frac{\sqrt{lg}}{A} \cdot \frac{\sqrt{B}}{D}}$$

In the foregoing, the term A is called "design

constant" and the term B is called "dimensioning constant," and the last-mentioned equation is expressed as $t = A \cdot D$.

It was found theoretically and by tests that for any given design the constant A can be varied only within very narrow limits while the dimensioning constant D is readily susceptible to change and hence represents the essential criterion for the duration of the switching period t . This explains the significance of the relation

$$\frac{\sqrt{lg}}{B}$$

used in the foregoing description of the invention.

For the derivation just given, the assumption was made that the air gap induction disappears suddenly at the commencing moment of spring biased armature motion. In reality, the gap induction does not vanish immediately but retains some decaying impediment effect on the armature movement. Hence, if the switching period t is calculated for

$$D = \frac{\sqrt{lg}}{B}$$

with B being the initial inductance (B_H), the resulting value is smaller than the time actually measured. It was found, however, that sufficiently accurate results are obtained if the value B in the foregoing equations is defined not as the initial inductance (B_H) but is given the approximate value of the mean magnetic induction in the air gap, this value B being smaller than the initial induction. Hence, the mean magnetic induction is referred to in the foregoing specification.

I claim:

1. An electromagnetic switching device for switching periods below 3×10^{-4} sec., comprising an electromagnet structure having two electrically conductive poles with respective pole faces mutually spaced and electrically insulated from each other to form stationary switch contact surfaces, a rigid and electrically conductive armature rotatable between two positions and biased toward one of them, said armature having substantially coincident gravity and pivot axes and being pivoted between said pole faces and provided with contact faces opposite said respective pole faces so as to form respective air gaps when said armature is in said one position, said armature having a magnetically effective cross-sectional area approximately equal to that of each armature contact face and having a magnetically effective length l correlated to the length g of each air gap and to the mean magnetic induction B of said gap so that the value

$$\frac{\sqrt{lg}}{B}$$

is below 1.5×10^{-5} cm./gauss.

2. An electromagnetic switching device for switching periods below 3×10^{-4} sec., comprising an electric circuit, a stationary switch structure having an electromagnet and having rigid contact means connected with said circuit, a rigid magnet armature having a magnetic flux path in common with said magnet and being movable between two positions toward and away from said magnet, spring means connected with said armature and biasing it away from said magnet, said armature being electrically engageable with said contact means in one of said positions to close said circuit through said armature, said armature

ture and said magnet forming together an air gap when said armature is in said one position away from said magnet, said armature and said gap having along said path respective lengths (l and g) correlated to the mean magnetic induction B in said gap so that the value

$$\frac{\sqrt{lg}}{B}$$

is below 1.5×10^{-5} cm./gauss.

3. An electromagnetic switching device for switching periods below 3×10^{-4} sec., comprising rigid stationary contact elements electrically insulated from each other, an electromagnet and a rigid armature structure having a common magnetic flux path, said armature structure being movable between open and closed positions relative to said contact elements to form a rigid contact bridge when in said closed position, said magnet and said armature structure forming together an air gap in one of said armature positions, said armature structure having along said path a length l of at most about 1 cm., and said gap having along said path a length g correlated to said armature length and to the mean magnetic induction B in said gap so that the value

$$\frac{\sqrt{lg}}{B}$$

is below $.5 \times 10^{-5}$ cm./gauss.

4. An electromagnetic switching device for switching periods below 3×10^{-4} sec., comprising rigid stationary contact elements electrically insulated from each other, an electromagnet and a rigid armature having a common magnetic flux path, said armature being movable between open and closed positions relative to said contact elements to form a rigid contact bridge when in said closed position, said magnet and said armature forming together an air gap when said armature is in said open position, said gap having along said path a length g of at most about .01 cm., and said armature having along said path a length l correlated to said gap length and to the mean magnetic induction B in said gap so that the value

$$\frac{\sqrt{lg}}{B}$$

is below $.5 \times 10^{-5}$ cm./gauss.

5. An electromagnetic switching device for switching periods below 3×10^{-4} sec., comprising rigid stationary contact elements, an electromagnet having a pole face, a rigid armature having a common magnetic flux path with said magnet and having a pole face opposite that of said magnet, said armature being movable between contact closing and contact opening positions relative to said stationary contact elements and being biased to one of said positions, said pole faces being spaced from each other by a given air gap when said armature is in said one position, said armature having a magnetically effective cross-sectional area approximately equal to that of said armature pole face, and said armature and said gap having along said path respective lengths (l and g) correlated to the mean magnetic induction B in said gap so that the value

$$\frac{\sqrt{lg}}{B}$$

is below 1.5×10^{-5} cm./gauss.

6. In an electromagnetic switching device according to claim 3, said armature having an elec-

tric resistance at most equal to the contact resistance obtaining between said armature and said stationary contact means when said armature is in said circuit closing position.

7. An electromagnetic switching device according to claim 3, comprising biasing means tending to move said armature to one of said positions in opposition to the attractive force of said magnet, said biasing means having a force of at least 20% of that of said magnet when said armature is in attracted position. 10
